UNITED STATES PATENT OFFICE.

JOHN HYDE, OF KNOXVILLE, PENNSYLVANIA; CATHERINE HYDE ADMINISTRATRIX
OF SAID JOHN HYDE, DECEASED.

PULVERIZER.

1,118,775.

Specification of Letters Patent.

Patented Nov. 24, 1914.

Application filed October 24, 1912. Serial No. 727,573.

To all whom it may concern:

Be it known that I, JOHN HYDE, a resident of Knoxville, in the county of Allegheny and State of Pennsylvania, have invented a new and useful Improvement in Pulverizers, of which the following is a full, clear, and exact description, reference being had to the accompanying drawings, forming part of this specification, in which—

10 Figure 1 is an end view of one form of my improved pulverizer in which I have shown a portion of a furnace to which pulverized fuel is fed from the pulverizer. Fig. 2 is a plan view of the nozzle leading from 15 the fan to the furnace. Fig. 3 is a side elevation of the pulverizer. Fig. 4 is a vertical longitudinal sectional view through the pulverizer. Fig. 5 is a sectional view on the line V—V of Fig. 4. Fig. 6 is a sectional view on the line VI—VI of Fig. 4; and Fig. 20 7 is a detail sectional view on the line VII—VII of Fig. 4.

This invention relates to pulverizers and is designed to provide a cheap and efficient device of this character to continuously pulverize material which is drawn from one end thereof and deliver to the point where it is to be used or stored by a current of air passing through the pulverizer.

25 The device is particularly adapted for feeding pulverized fuel to a furnace, although it can readily be used for pulverizing ores, stone or any coarse material which is to be reduced to a powder.

30 The precise nature of my invention will be best understood by reference to the accompanying drawings which will now be described, it being premised, however, that various changes may be made in the details 35 of construction and general arrangement of the parts, without departing from the spirit and scope of my invention, as defined in the appended claims.

Referring to the accompanying drawings, 40 the numeral 2 designates the frame work or support for the pulverizing drum 3, which is rotatably mounted on rollers 4 connected to shafts 5 journaled in the frame 2. The drum 3 comprises a tubular shell of sheet metal, and mounted on the outer periphery of the shell are flanged collars 6, to which are secured heads 7. Formed integrally with one of the collars 6 is a circular rack

8 which is in mesh with a pinion 9 on a shaft 10, which is also journaled in the frame 2. 55

The interior of the pulverizer is divided into a plurality of compartments 11, 12, 13 and 14 by means of partitions 15, 16 and 17; the compartments gradually decreasing in width from the inlet end to the outlet end of 60 the pulverizer. The central portions of the partitions are provided with openings 18, and adjustably mounted on rods 19 secured to various partition plates are baffles 20, the diameters of which are greater than the 65 openings 18. These baffles are spaced a slight distance from the partitions for the purpose hereinafter described.

21 designates the casing of a feeding device which is supported on a bracket 22 extending upwardly from the base of the frame 2. Journaled in bearings in the ends of the casing 21 is a shaft 23 which is provided with a spiral feeding device 24 within the casing and a driving pulley 25 on the 75 outer end of the shaft.

26 designates a hopper for receiving the material to be pulverized which is connected to the casing 21. The end of the casing 21 which is of cylindrical form extends 80 through an opening 27 in one of the heads 7, there being an open space between the walls of said opening and the outer wall of the casing 25 for permitting air to pass into the pulverizer between said casing and the walls 85 of the opening.

28 designates a valve mounted on the casing 21 and arranged to increase or decrease the size of the inlet ports leading to the opening 27. 90

Mounted on the top of the frame 2 is a fan casing 29, and rotatably journaled in said fan casing, and a bracket 30 on the other end of the frame, is a shaft 31.

32 designates a rotary fan within the casing 29 connected to the shaft 31 and 33 is a pulley on the opposite end of said shaft.

34 is a pipe extending through a central opening in the head 7 at the outer end of the pulverizer and is also connected to the fan casing 29. Extending from the outlet end of the fan casing 29 is a nozzle 35 which leads to a furnace 36, or other suitable point, to which the pulverized material is delivered. 100

In the preferred embodiment of my in-

vention, as shown in the drawings, I have shown the various compartments built up of the partitions 15, 16 and 17, and shells 37, 38, 39 and 40. Connected to the inner 5 face of the shell of the drum 3 is a spline 41. Each of the shells 37, 38, 39 and 40 are provided with a groove for the reception of spline 41, as shown in Fig. 6. The shells 37 to 40, together with the partition plates 15 10 to 17 are inserted into the drum and the heads 7 are then secured to the flanges on the ring 6. These shells are preferably formed of malleable castings, so that they will withstand the pounding effect of the balls 42 15 within the compartments. The shell 40 of the last or smallest compartment, is provided with a plurality of ribs 43 which are designed to raise the balls in that compartment during the rotation of the drum, so 20 that they will fall on the material in the last compartment to completely pulverize any material which has been drawn therein, as hereinafter described.

I prefer to place larger balls in the compartment 11 than in the remaining compartments and if desired, I can gradually decrease the size of the balls in the compartments toward the outlet end of the pulverizer.

30 Mounted on the frame 2 is a motor 44 having a pulley on the end thereof which is connected by means of a belt 45 with a pulley on the shaft 10, for rotating the drum 3 through the medium of the gearing.

35 46 is a belt connecting a pulley on the shaft 10 with the pulley 25 of the feeding device and 47 is a belt connecting another pulley on the shaft 10 with the pulley 33 on the fan shaft 31.

40 The operation of the device is as follows: After the motor has been started to rotate the fan, drum and feeding device, fuel or material to be pulverized is fed into the hopper 26, the blast of air passed from the pulverizer to the delivery pipe or nozzle 35 will draw all of the powdered material through the various openings 18, as well as from the feeding device, while the feeding device will feed the coarser material into the first compartment 11. The rotation of the drum will

45 raise the balls in the various compartments as well as the material therein, and during the tumbling of the balls and the material within the compartments, said material will be reduced to a powder before passing from the last compartment. The baffle 20 can be moved toward or from the division plates in order to gage the size of the material passing from one compartment to the next compartment. The number and size of these compartments can be varied to meet the requirements for crushing various materials, and quantity of material in a given period of time. If there is not sufficient air passing 55 through the feeding device, additional air is

admitted between the casing of the feeding device and the walls of the opening 27 by adjusting the valve 28.

The advantages of my invention result from the provision of a rotary pulverizing 70 drum having a plurality of partitions therein, the partitions having openings with baffles arranged adjacent thereto.

A further advantage results from the provision of means for continuously feeding the material to be pulverized into one end of the drum, together with means for exhausting the pulverized material from the other end and delivering it to a predetermined point.

I claim:

1. A pulverizer having a rotatable drum, a feed device extending into one end of the drum concentric therewith, an outlet pipe extending through the other end of the drum and concentric therewith, a plurality of division plates within said drum which divide the drum into a plurality of compartments, there being a central opening through each of said division plates, said openings forming the only communication between the compartments, a baffle connected to each partition in front of the opening through said partition and arranged to prevent pulverized material from passing in a direct line through the openings in two partitions, means for rotating said drum, means for pulverizing the material in each compartment when the drum is rotated, there being an opening for the admission of air surrounding the feeding device, and an exhaust fan connected to the outlet pipe for drawing the pulverized material from the drum; substantially as described.

2. A pulverizer having an opening through each end, said openings being concentric with the center thereof, means for rotating said pulverizer, a feeding device extending through the opening at one end thereof, there being an air space surrounding the wall of the feeding device, the end of the drum being provided with openings communicating with said space, a slide device having air inlet openings therethrough arranged to register with the air inlets communicating with the space surrounding the feeding device, and an exhaust fan having a connection extending into the opening in the other end of the pulverizer, substantially as described.

3. A pulverizer having a rotary drum, an annular flange at each end of the drum, concentric with the axis thereof, there being an annular opening through each of said flanges, means for rotating said drum, an exhaust pipe extending through the annular opening in one end of the drum, said drum being arranged to rotate about said exhaust pipe, a feeding device extending 125

through the annular opening in the other end of the drum, there being an air space surrounding the feeding device, and a slide plate rotatably mounted about the feeding device and arranged to adjust the size of feed openings communicating with the air space, substantially as described.

In testimony whereof, I have hereunto set my hand.

JOHN HYDE.
